MINIATURE TRAFFIC LIGHT AND TURN SIGNAL FOR VEHICLES

Hyman Reingold, Brooklyn, N. Y.

Application September 11, 1952, Serial No. 21,411

Term of patent 14 years

(Cl. D72—1)

To all whom it may concern:

Be it known that I, Hyman Reingold, a citizen of the United States, residing at Brooklyn, in the county of Kings and State of New York, whose post office address is 1590 West Eighth Street, Brooklyn, New York, have invented a new, original, and ornamental Design for a Miniature Traffic Light and Turn Signal for Vehicles, of which the following is a specification, reference being had to the accompanying drawing, constituting a part hereof.

Fig. 1 is a perspective view of a miniature traffic light and turn signal for vehicles, showing my new design;

Fig. 2 is a top plan view;

Fig. 3 is a rear elevational view; and

Fig. 4 is a bottom plan view.

The drawing is lined to indicate contrasting colors.

I claim:

The ornamental design for a miniature traffic light and turn signal for vehicles, substantially as shown and described.

HYMAN REINGOLD.
